UNITED STATES PATENT OFFICE.

ARTHUR R. SPEER, OF PITTSBURG, PENNSYLVANIA.

WASHBOARD.

SPECIFICATION forming part of Letters Patent No. 666,085, dated January 15, 1901.

Application filed May 10, 1899. Serial No. 716,279. (No model.)

To all whom it may concern:

Be it known that I, ARTHUR R. SPEER, a resident of Pittsburgh, in the county of Allegheny and State of Pennsylvania, have invented a new and useful Improvement in Washboards, (Case B;) and I do hereby declare the following to be a full, clear, and exact description thereof.

My invention relates to washboards, its object being to provide for the draining of the water back over the surface of the board and at the same time protect the person using the board from the water raised by the rubbing action.

15 My invention comprises certain details of construction, all of which will be hereinafter fully set forth and claimed.

To enable others skilled in the art to make and use my invention, I will describe the 20 same more fully, referring to the accompanying drawings, in which—

Figure 1 is a perspective view of my improved washboard. Fig. 2 is a vertical section of same. Fig. 3 is a cross-section on the 25 line 3 3, Fig. 2. Fig. 4 is a cross-section on the line 4 4, Fig. 2.

Like letters of reference indicate like parts in each.

The letter *a* designates the sides of the 30 washboard, with the leg portions at the lower end thereof, by means of which the washboard is supported. The back *b*, which supports the corrugated metal plate *c*, which forms the rubbing-surface, has the tongues *d*, adapted 35 to enter the grooves *e*, formed on the inner faces of the sides *a*. The side edges of the metal rubbing-plate *c* also enter grooves *e*, the lower horizontal portion of said plate entering the seat *g* in the lower cross-bar *h*. 40 The upper horizontal portion of the rubbing-plate *c* enters a seat *i*, formed in the inclined cross-bar *k*, the ends of said cross-bar fitting in the seats on the inner face of said sides *a*.

A back *m* at the upper end of the board 45 has its lower edge fitting in a seat *n* in the inclined cross-bar *k* and its upper edge fitting in a seat *n'* in the upper cross-piece *o*. The side edges of the back *m* fit within the seats *r* in the sides *a*. In this manner a very 50 secure support for the back *m* is obtained. Just in front of the back *m* is the back *s* of

the soap-holder, said back being supported by the sides *a* and upper cross-bar *o*. The shelf *t* of the soap-holder is secured within seats in the sides *a*, a space *t'* being left between the lower edge of the back *s* and the shelf *t* to permit the water to escape from 55 said shelf.

When my improved washboard is in use and the wet clothes are rubbed up and down the rubbing-surface, the water thrown up by the rubbing action will pass up between the backs *m* and *s* and will then flow back over the inclined bar *k* onto the rubbing-surface, the water being thus all drained over the rubbing-surface. Any water carried by the soap 60 when placed upon the shelf *t* will drain off through the space *t'* back onto the board, thus preventing waste of the soap caused by its remaining in the water which has been carried by it onto the end of the soap-holder. 65

What I claim as my invention, and desire to secure by Letters Patent, is—

1. In a washboard, side pieces supporting 75 a back, a metal rubbing-plate covering said back, an inclined cross-bar at the upper end of said back, the upper edge of said rubbing-plate fitting in a groove in the lower front side of said inclined bar, and an upper back having its lower edge fitting in a seat in the 80 upper rear side of said inclined cross-bar and its upper edge fitting in a seat in the top cross-bar, substantially as set forth.

2. In a washboard, a top cross-bar, sides 85 supporting a back and rubbing-plate, a cross-bar at the upper end of said rubbing-plate, an upper back engaging said cross-bar and the sides and top cross-bar, a separate back for a soap-holder supported by said sides leaving a space between the upper back and the 90 soap-holder, and a shelf supported by said sides to leave an opening between said shelf and said soap-holder back, whereby the water is permitted to escape, substantially as set forth.

In testimony whereof I, the said ARTHUR R. SPEER, have hereunto set my hand.

ARTHUR R. SPEER.
